Primary Examiner—Lisa P. Lichtenstein
Attorney, Agent, or Firm—Richard C. Litman[57] **CLAIM**

The ornamental design for a portable collapsible combined mat and body rest, as shown and described.

DESCRIPTION

FIG. 1 is a front perspective view of a portable collapsible combined mat and body rest showing my new design;
 FIG. 2 is a rear perspective view of a portable collapsing mat and body rest showing my new design;
 FIG. 3 is a top plan view thereof;
 FIG. 4 is a front elevational view thereof;
 FIG. 5 is a right side elevational view with the left side view being a mirror image thereof; and,
 FIG. 6 is a rear elevational view thereof.
 The bottom is plain and unornamented.
 The cross-hatching represents conventional fabric and is understood to extend throughout the areas represented. The broken lines represent stitching.
